J. H. MOELLER.
VARNISHING MACHINE.
FILED NOV. 9, 1920.

UNITED STATES PATENT OFFICE.

JOHN H. MOELLER, OF ST. LOUIS, MISSOURI, ASSIGNOR TO THE GOODYEAR'S METALLIC RUBBER SHOE COMPANY, A CORPORATION OF CONNECTICUT.

VARNISHING MACHINE.

Application filed November 9, 1920. Serial No. 422,834.

To all whom it may concern:

Be it known that I, JOHN H. MOELLER, a citizen of the United States, residing at St. Louis, State of Missouri, have invented 5 a certain new and useful Varnishing Machine, of which the following is a full, clear, and exact description.

This invention relates to a varnishing machine, and more particularly to a machine 10 for varnishing vulcanizable articles such as footwear, prior to the vulcanizing operation.

Machines of this general type are well-known, such machines consisting of a tank 15 for varnish, and a support pivotally mounted at the side of the tank for removably holding a so-called shoe stick containing the articles which are to be varnished or dipped. The shoes or other footwear are 20 mounted on the lasts on which they have been made, these lasts having sockets adapted to slidably receive pins mounted on the shoe stick and support the shoes and lasts in inverted position on the stick. Hence, when 25 the support carrying the shoes is swung on its pivot to immerse the shoes in the tank in upright position the shoes and the lasts on which they are supported are liable to drop off the pins on the shoe stick unless some 30 means is provided for retaining them in position during the dipping or varnishing operation. To prevent the shoes from dropping off a bar is pivotally mounted on the tank in position to be engaged by the shoes 35 as they are swung down into the tank, this bar having connected thereto a counter-balance or other means for yieldably resisting the movement of the shoes into the tank. The shoe supporting means is also provided 40 with counter-balancing means to aid in returning it after the dipping operation. The counterbalance for the shoe engaging bar has usually been mounted at the side of the tank and in a position to interfere more or 45 less with the movements of the operator when dipping the shoes.

The objects of my invention are to provide a simple and easily operated varnishing machine having a minimum number of 50 parts and so constructed that none of the parts will be in the way of the operator using the machine.

For a detailed disclosure of the invention reference is had to the accompanying specification and drawings, in which latter:

55

Fig. 1 is a side elevation of the machine;

Fig. 2 is a front view thereof; and

Fig. 3 is a detail illustrating the manner in which the shoe stick is supported.

Referring to the drawings the numeral 1 represents a frame on which is mounted the tank 2 for the varnish, the latter having sides 3 and extended ends 4. Leading from the bottom of the tank is a pipe 5 to which is connected a valve controlled inlet 6 and a valve controlled outlet 6'. At the upper edges of the sides 3 of the tank drain boards 7 are provided, and adjacent each end of each drain board is a bracket 8 having a bearing surface 9 at its top upon which rests an arm 10 pivotally connected to the bracket at 11. Pivotally connected to a pair of arms 10 at 12 is a wide U-shaped frame having end portions or legs 13 and a connecting portion 14, to which latter is secured 65 a handle 15. Secured to the free end of each leg 13 is a channel-shaped member 16, the channel 17 of which, however, does not extend entirely through the member 16 as shown in Fig. 1. The ends of the shoe stick 18 fit slidably in the channel 17 and pairs 70 of retaining pins 19 are mounted at intervals on the stick. The lasts 20 carrying the footwear articles 21 are provided with pairs of sockets in the usual manner, and 75 with which the pins 19 engage. Rigidly secured to each leg 13 is a curved arm 22 to the end of which is pivotally connected a link 23 which is in turn rigidly secured to one end of the shoe engaging bar 24. Also 80 connected to the ends of the bar 24 are cables 25 extending over pulleys 26 and carrying weights 27 on their opposite ends. If desired the dipping mechanism may be duplicated on each tank, as shown in Fig. 1. 85

In operation the shoe sticks carrying the lasted shoes are mounted in racks on small cars, and the operator passes rapidly from one varnishing machine to the next, removing sticks of shoes from the racks and inserting one in the shoe stick supporting frame of each machine and then grasping the handle and swinging the frame inwardly and downwardly to immerse the shoes in 90

95

100

the contents of the tank. The parts are then returned to the position shown at the right hand side of Fig. 1 and the shoes left to drain. It will be noted from Fig. 1 that 5 while the shoes are in the position shown at the right hand side of the figure they are substantially inverted and they and their supporting lasts remain in position on the pins 19. As the shoes pass the position 10 shown at the left hand side of Fig. 1, however, and begin to assume the upright position shown in the center the lasts and shoes tend to slip off the pins 19, but due to the downward movement of the arms 22 as the 15 U-shaped frame swings on its pivots 12 the shoe engaging bar 24 is brought to the position shown at the left hand side of Fig. 1 and engages the shoes thereby preventing displacement of the lasts and shoes during 20 the dipping operation. By reason of the weights 27 the bar 24 is held firmly against the shoes and these weights also return the bar 24 and the shoe supporting frame to the position shown at the right hand side 25 of Fig. 1. Any equivalent of the weights may be used instead.

It will be seen that by my invention a varnishing machine has been provided which can be operated by one hand, which consists of a minimum number of parts, in 30 which a single set of weights acts to counter-balance and return both the shoe supporting frame and the shoe engaging bar, and in which all of the mechanism of the machine 35 is disposed entirely out of the way of the operator.

While a specific adaptation of the invention has been shown and described it is obvious that numerous changes may be made 40 in the machine within the scope of the appended claims, and it is not limited in its application to the dipping or varnishing of footwear.

Having thus described my invention, what 45 I claim and desire to protect by Letters Patent is:

1. In a liquid coating machine, a tank, pivotally mounted means for loosely supporting the articles to be coated adjacent the 50 tank, means whereby said first means may be moved to immerse the articles in the tank, and unitary means carried by the supporting means for preventing dislocation of the articles on the support during immersion and returning said pivotally mounted means to inoperative position after immersion of the articles.

2. In a liquid coating machine, a tank for the liquid, pivotally mounted means for 55 loosely supporting articles either in inverted position at the side of the tank or in upright position within the tank, and unitary means carried by the supporting means engaging the articles while within the tank to prevent 65 dislocation thereof and tending to return

said pivotally mounted means to inoperative position and the articles to inverted position after immersion at the side of the tank.

3. In a varnishing machine, a tank, a footwear support pivotally mounted on said tank, means carried thereby for loosely holding the footwear in inverted position, means for rotating the support to immerse the footwear in the tank in upright position, and unitary means carried by the support 70 and operative upon rotation thereof to engage the footwear to prevent displacement thereof and tending to return said support to inoperative position and the footwear to inverted position at the side of the tank. 75

4. In a varnishing machine, a varnish tank, a supporting arm pivotally mounted thereon, a footwear carrier pivotally carried by said supporting arm, footwear retaining means pivotally connected at one 80 end to said carrier, and means connected to the other end of said retaining means for yieldingly maintaining said supporting arm and parts carried thereby at one side of the tank. 85

5. In a varnishing machine, a varnish tank, arms pivoted at the side thereof, a shoe stick supporting frame pivoted to said arms, arms rigidly connected to said frame, a shoe retaining bar pivoted to said last 90 named arms, and counter-balancing means supported by said bar and operating there-through thereby tending to return the supporting frame to inoperative position after immersion. 95

6. In a varnishing machine, a tank, arms pivotally mounted at the side of said tank, means pivoted on said arms for loosely holding footwear articles in inverted position, means for turning said last means on 105 its pivots and said arms on their pivots to thereby immerse the footwear in said tank in upright position, and means connected to said pivoted means and operative to engage the footwear to prevent displacement there- 110 of during immersion.

7. In a varnishing machine, a varnish tank, arms pivoted at the side thereof, a shoe stick supporting frame pivoted to said arms intermediate its ends, an operating 115 handle secured to one free end of the frame, means for supporting a stick of shoes disposed at the other free end, curved arms rigidly connected to said frame at one side of its pivot point, a shoe retaining bar pivotally 120 mounted on said curved arms, and counter-balancing means connected to said bar.

8. In a varnishing machine, a varnish tank, pivotally mounted means including an arm pivotally secured to the side of the 125 tank for loosely supporting footwear in one position at the side of the tank or in an inverted position laterally therefrom within the tank, movable means carried by said first means for engaging the footwear 130

as it is swung bodily laterally into the tank to prevent displacement thereof, and means connected to said last means and disposed above the tank for yieldingly resisting the inward movement of said first two means.

9. In a varnishing machine, a varnish tank, pivotally mounted means including an arm pivotally secured to the side of the tank for loosely supporting footwear at one side of the tank, whereby the footwear may be swung bodily laterally into the tank, a footwear engaging bar disposed in the path of the footwear and pivotally carried by said means, and means connected to said bar for yieldingly resisting displacement thereof by the footwear.

10. In a varnishing machine, a tank, arms pivotally connected to the side of the tank

adjacent its top, a shoe stick supporting frame pivoted between said arms, means whereby said parts and the supported shoes may be swung down into the tank, a shoe engaging bar pivotally carried by said frame and disposed in the path of the shoes, and means disposed out of the way of the operator and supported by said bar for yieldingly resisting displacement of said bar during the said downward swinging and operating therethrough in the upward movement thereby tending to return the supporting frame to inoperative position after immersion and to disengage said bar from the shoes.

Signed at St. Louis, Missouri, this first day of November, 1920.

JOHN H. MOELLER.
